(57) **CLAIM**

The ornamental design for a set of nail clippers with integrated nippers, as shown and described.

DESCRIPTION

FIG. 1 is a top perspective view of a set of nail clippers with integrated nippers showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective view thereof showing the lever in an upwards position; and,

FIG. 10 is a top perspective view thereof showing the lever in a downwards position.

The broken line showing a lever in FIGS. 9-10 is included for the purpose of illustrating environmental structure and forms no part of the claimed design.
